UNITED STATES PATENT OFFICE.

JOHN AGAR; OF EAST ORANGE, NEW JERSEY.

HAT-BRIM-CURLING MACHINE.

SPECIFICATION forming part of Letters Patent No. 603,719, dated May 10, 1898.

Application filed April 20, 1895. Serial No. 546,467. (No model.)

To all whom it may concern:

Be it known that I, JOHN AGAR, a citizen of the United States, residing at East Orange, in the county of Essex and State of New Jersey, have invented certain new and useful Improvements in Hat-Brim-Curling Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to facilitate the operation of curling hat-brims, to attain more perfect and satisfactory results, and to secure other advantages hereinafter referred to.

20 The invention consists in the improved machine and in the arrangement and combination of the parts thereof, as hereinafter set forth, and finally pointed out in the claims.

Referring to the accompanying drawings, 25 in which similar letters of reference designate corresponding parts in each of the figures where they occur, Figure 1 represents in side elevation a hat-brim-curling machine embodying my improvement; Fig. 2, a top plan 30 view of the same. Fig. 3 represents in section a certain flanged wheel, gear, and shaft, the latter being in elevation and exhibiting a modified form of the said wheel and gear. Fig. 4 represents in perspective a certain 35 curler shown in plan in Fig. 2. Fig. 5 represents in perspective a certain guide, also shown in plan in said Fig. 2. Fig. 6 is an enlarged detail elevation showing the relations of the parts which act immediately upon the 40 hat-brim to curl the same more clearly, and Fig. 7 is a section taken at line x.

In said drawings, A designates a frame or housing in and upon which the working parts of the machine are mounted, said housing being supported and fastened upon a suitable table or support B. C designates a shaft journaled in said housing and upon which is rigidly mounted a wheel D, the periphery of which is provided with a curved flange a. 45 Said wheel may be solid or provided with a central chamber b, as indicated in Fig. 3. Upon the top of the flanged wheel D is secured

a gear b', the object of which will be described farther on.

E designates a presser-wheel, the periphery 55 of which is convex and serrated, mounted and rotating upon a shaft c, arranged vertically and pivotally in a portion of the housing or frame, said shaft being provided with a slot d to admit of a limited vertical movement. 60 There is also secured upon the top of the said wheel E a gear e, which when the machine is in operation meshes with the gear b'. Around said vertical shaft c is arranged a coiled spring f, which engages with a stop-pin 65 f' in said shaft and with the bearing in which said shaft is mounted, the normal tendency of said spring being to hold the wheel E up, so that its upper and convex peripheral portions bear against the flanged periphery of 70 the wheel D. This stop-pin is so arranged that the tension of the spring may be increased or diminished by turning the latter one way or the other around said shaft, as will be understood upon reference to Fig. 1. To the 75 top of said shaft is connected a rod g, which passes from thence loosely through a portion h of the frame or housing and the end thereof connecting with a cord i, which passes over a pulley j, and thence to a foot-treadle (not 80 shown) upon the floor, by means of which the wheel E may be thrown outward away from the flanged wheel, or the pressure of the former against the latter be regulated, as will be understood. Coiled around said rod g is also 85 a spring s, one end of which abuts against said vertical shaft and the other against the portion of the housing or other suitable stop, the purpose of which is to hold the wheel E normally toward and into engagement with the 90 flanged wheel or, rather, the hat-brim while the curl thereof is being formed, as will be plainly understood upon reference to Fig. 1. In order to heat and keep said flange-wheel heated properly, I have arranged a jet k, which 95 may be connected with any suitable source of supply, whereby a flame may be thrown against the periphery of said wheel, as will be understood by reference to said Fig. 1, or into a central chamber formed therein, as will 100 be understood upon reference to Fig. 3.

At the lower end of the shaft upon which the flanged wheel is mounted is arranged a gear l, which is secured upon said shaft by

means of a screw passing through the hub thereof or in any suitable manner. Said gear meshes with a driving-gear o , mounted upon a shaft p , which is driven by means of a pulley m , secured upon said shaft by means of a cord or belt n , which connects with a power-wheel, (not shown,) as will be understood upon reference to Fig. 1.

In order to facilitate and perfect the curling of the hat-brim, I have provided in connection with the concavously-flanged wheel D convexed smaller wheel E , means for rotating the same and holding them in curling relation to the brim with a yielding pressure, 10 a guide P , which is adjustably secured upon a small tablet O of the frame A , which tablet lies in a plane near to and closely parallel with the plane of the hat-support, so that the hat-brim resting on said support and after passing 15 between the wheels D E will enter the curved passage p' of said guide. The inner turned end of said adjustable guide lies closely adjacent to the convex periphery of said wheel E and enters beneath the flange a , the 20 parts being disposed so that the extremity of the returned end p'' will lie on a level with the flange a , the concavity p' will correspond with the concavity underneath said flange, and the edge p''' will lie close to the body of 25 the wheel D at the periphery, so that there will be a continuous bearing extending from the periphery of the wheel D over the guide P , against which the felt may be pressed as it travels forward. The wheel E lies opposite 30 the joint formed at edge p''' and presses the felt on both parts, as will be understood upon reference to Figs. 6 and 7, and thus a more extended ironing or curling surface is secured than if the two convexities of the wheel-peripheries alone were employed. It may be noted that the wheel E presses upward against both the flange a and returned portion p'' , 35 curling the brim, so that there is a larger compression - surface horizontally between the parts E , D , and P as well as vertically. The guide may be adjusted by means of the slot r and fastener t therein, as occasion may require. The hat-brim when acted upon by the parts thus described is given a curl which 40 is sufficient and satisfactory in certain grades of work; but in other and finer varieties and to obtain a more perfect and uniform curl and to increase the curvature without producing kinks, creases, or the like I ordinarily 45 and preferably employ an additional part q , which I have termed a "curler." This also is secured upon the tablet O and consists of a bed-plate q' , having a longitudinally-curved and forwardly-bent flange q'' , by which a 50 cavity q''' , corresponding with the concavity p' , is formed. At its upper edge said curved and bent flange q'' is provided with a vertical supplemental flange or flanges q'''' , which forms a seat or seats upon which a longitudinally-curved and downwardly, inwardly, and 55 then upwardly bent plate or piece q''''' is secured by fastening-screws u . The chamber

q''''' , formed by the parts q'' q''''' is, when viewed endwise, of helical shape, as shown in Figs. 4 and 6, and contracts as it extends 70 away from the wheels D E , as will be understood upon reference to Fig. 6.

The curled brim on entering the part q is of a simple **C** shape, due to the operation of the wheels D E and guide P , but immediately in passing through said curler the upper edge of said brim is given a downward turn and then an upward turn, the felt being curled over itself and the curl being gradually made tighter or smaller while yet hot, so 80 that all creases or kinks are removed. When the felt passes from out the curler, the resiliency of the felt occasions an opening up of the curl to some extent; but the effect of giving a helical roll to the felt, as indicated, 85 is beneficial, in that it produces a peculiar smoothness and finish of particular value.

The tapering chamber in the curler may be made larger or smaller by manipulating the fastening-screws u and employing washers between the parts q'''' q''''' .

It will be observed that the curler is curved longitudinally to conform to the curvature of the brim. The serration of the convex periphery of the wheel E is to increase its grip 95 upon the felt and enable it to force the same forward into the curler without slipping, so that the work of curling may be more perfectly automatic.

In operation the hat-brim is inserted 100 between the wheels E D and adjusted within the guide P and curler q . Upon setting the machinery in operation the brim is fed automatically forward by the action of the wheels upon the felt. Said wheels also give an initial turn to the felt as the latter passes therebetween, and the heated wheel imparts the necessary heat to said felt, so that the operation is rendered more effective and the shape retained. From the wheels the felt 105 passes immediately upon the **C**-shaped surfaces of the guide P . Here the shaping operation is continued. The small convex wheel E presses the felt against both the flange of the wheel D and the upper and lower sides 110 of the **C**-shaped portion of the guide, so that the felt is given a comparatively smooth and even **C**-shaped bend.

While the greater pressure and working is brought to bear upon upper inwardly-extending portion of the curled felt, the lower curved portion of the guide lying opposite the flange a , coöperating with the convex wheel, produces enough pressure to secure the desired result effectively. Passing from the guide 115 P the felt, having the **C**-shaped curve, passes into the curler q , where the felt is increased in curvature and given downward and inward bends at its edges. As it travels through the curler the curl is gradually tightened or 120 made smaller in diameter, and thus, after the felt issues therefrom and tends to assume its original shape because of the resiliency of the felt, it will yet retain an increased curl 125 130

and a curl that is more perfect and free from defects, so that the machine can be used effectively and with satisfaction upon a higher class of work.

5 Having thus described my invention, what I claim as new is—

1. In a hat-brim-curling machine, the combination with the frame or housing, of a shaft journaled vertically therein; a flanged wheel rigidly mounted upon said shaft, a gear-wheel rigidly connected with said flanged wheel, a vertically and laterally movable shaft mounted in the housing, a wheel E, having a convex periphery mounted upon the lower end 15 of said shaft, a gear-wheel secured to said wheel E, meshing with the gear of said flange-wheel, means for rotating said flange-wheel and means for operating said shaft vertically and laterally as described, and for the purposes set forth.

2. In a hat-brim-curling machine, the combination with the frame or housing thereof, of a shaft journaled vertically therein; a flanged wheel rigidly mounted upon said shaft; a gear-wheel rigidly connected with said flanged wheel; a slotted shaft vertically mounted in the housing, a pin in the housing through the slot whereby the shaft is capable of a vertical and lateral movement; a wheel 30 E, having a convex and serrated periphery mounted upon the lower end of said shaft; a gear-wheel secured to said wheel E, meshing with the gear of said flanged wheel and means for operating said shaft vertically and laterally as described and for the purposes set forth.

3. In a hat-brim-curling machine, the combination with the flanged wheel and the wheel having a convex periphery of an adjustable 40 guide P, arranged beneath the flange of said flanged wheel, and having a concaved way or passage p', corresponding with the concavity on the periphery of the said flanged wheel, the wheel having the said convex periphery being arranged to press the felt against both said guide and flanged wheel, and means for operating said wheels, substantially as set forth.

4. In a hat-brim-curling machine, the combination with the flanged wheel and the wheel having a convex periphery and means for operating said wheels, of a guide to operate in conjunction with said wheels to receive the curled hat-brim and to fix the curve thereof, 50 a curler supplemental to said flanged and curved wheels to receive the hat-brim as it passes through said guide and to increase and perfect said curve therein and means for adjusting said guide and curler relative to each other and to the wheels as described, and for the purposes set forth.

5. In a hat-brim-curling machine, the combination, with the flanged wheel and the wheel having a convex periphery and means for operating said wheels, of a two-part curler q, having a curved passage-way through which the felt is forced by the wheels and screws

for holding said parts together, whereby the parts may be separated to a greater or less extent for adjusting the size of the passage-way, as described and for the purposes set forth. 70

6. In a hat-brim-curling machine, the combination, with the frame provided with a housing, of a vertically and laterally movable shaft mounted in the housing, the lower end of which is provided with a wheel having a convex periphery and the intermediate portion of which is provided with a pin, a coiled spring upon the shaft, one end of which engages with the housing, and a portion of the remainder of the spring engages with the pin, whereby the rotation of the spring around the shaft changes the tension of the spring and mechanism co-operating with said wheel 85 to curl the brim and means for operating said parts as described, and for the purposes set forth.

7. In a hat-brim-curling machine, the combination, with a frame, provided with a housing and a perforated portion, of a grooved wheel mounted in the frame, a shaft pivotally secured in the housing, the lower end of which is provided with a convex wheel, means for operating said wheels, a rod extending 90 from the upper end of the shaft through the perforated portion of the frame, a spring between the end of the shaft and the perforated portion, and a cord for moving the rod, as described and for the purposes set forth. 100

8. In a hat-curling machine, the combination with the flanged and convex wheels and means for operating and heating the same, of a curler q, adapted to receive the partly-curved felt after it leaves the said wheels, 105 said curler comprising an upwardly-curved part q'', and a downwardly-bent part extending from the upper part of said part q'', whereby the bent brim is given a downward bend at its edge, substantially as set forth. 110

9. In a hat-curling machine, the combination with the flanged and convex wheels, and means for operating and heating the same, of a curler, q, arranged adjacent to said wheel and adapted to receive the partly-curved hat-brim after leaving said wheels, said curler comprising an upwardly-bent part q'', and a downwardly and inwardly bent part q''', whereby the partly-curved brim is given a downward and inward bend approaching a 115 spiral shape at its edge, after leaving said wheels, substantially as set forth. 120

10. In a hat-curling machine, the combination with the flanged and convex wheels, and means for operating and heating the same, 125 of a curler q, arranged adjacent to said wheels and adapted to receive the partly-curved hat-brim after leaving said wheels, said curler comprising an upwardly-bent part q'', and a downwardly, inwardly and upwardly turned 130 part or extension q''', adapted to give to the partly-curved edge of the brim, a spiral twist or bend after it passes from between said wheels, substantially as set forth.

11. In a hat-curling machine, the combination with the flanged and convex wheels, and means for operating and heating the same, of a spiral and tapering curler, *q*, adapted to 5 give a spiral twist or bend to the edge of the hat-brim after it passes from said wheels, substantially as set forth.

12. In a hat-curling machine, the combination with the flanged and convex wheels, and 10 means for operating and heating the same, of a curved and tapering curler, adapted to receive the partly-curved brim after it passes from the said wheels and gradually increase and tighten the curl, substantially as set 15 forth.

13. In a hat-curling machine, the combination with the curling parts D, E, consisting of concave and convex members adapted to 20 give a partial curl to the brim, and means for heating the same, and moving the felt therebetween, of a curler *q*, curved and tapering in plan, and spiral in end view, substantially as and for the purposes set forth.

14. In a hat-curling machine, the combination with the concavously-flanged wheel, and 25 means for operating the same, the rotary shaft having the convex wheel, means for forcing the said convex wheel toward the flanged wheel with a yielding pressure of a 30 guide fixed adjacent to said flanged wheel, the convex wheel operating between said fixed guide and flanged wheel, substantially as set forth.

15. In a hat-curling machine, the combination with the concavously-flanged wheel, and 35 means for operating the same, the rotary convex wheel and means for operating the same, heating means and means for forcing said convex wheel toward said flanged wheel, of a 40 guide having a C-shaped part extending close to said flanged wheel, and presenting its concave surface to the convex wheel which supplements said flanged wheel in resisting the pressure of said convex wheel in curling the 45 brim, substantially as set forth.

16. In a hat-curling machine, the combination with the concavously-flanged wheel, and means for operating the same, the rotary convex wheel, and means for operating the same and heating means, of a fixed guide having a 50 C-shaped part extending underneath the flange of said flanged wheel into close relation to said flanged wheel, the convex wheel lying opposite the joint between said parts to press the felt against both parts, substantially as set forth. 55

17. In a hat-curling machine, the combination with the concavously-flanged wheel, and means for operating the same, the rotary convex wheel, and means for operating the same, 60 and heating means, of a guide having a flaring mouth extending into close adjacency to said flanged wheel, and supplementing the ironing and curling surface thereof, the convex wheel lying opposite both said parts and 65 pressing the felt against the two, substantially as set forth.

18. In a hat-curling machine, the combination with the flanged wheel, and convex wheel, and means for operating the same and heating 70 means, of a guide extending beneath the flange of the flanged wheel opposite the convex wheel, and a curler curved and tapering in plan and spiral in end view, and receiving the partially-curved brim, substantially as 75 and for the purposes set forth.

19. In a hat-curling machine, the combination, with a concavously-flanged wheel, of a convex wheel beneath said flange, a fixed guide adjacent to the periphery of the flanged 80 wheel, the convex wheel operating between said fixed guide and the flanged wheel, and operating devices, substantially as set forth.

In testimony that I claim the foregoing I have hereunto set my hand this 13th day of 85 April, 1895.

JOHN AGAR.
